S. O. MARTIN.
AUTOMOBILE SIGNAL DEVICE.
APPLICATION FILED FEB. 3, 1922.

Patented Dec. 5, 1922.

Fig. 1.

Fig. 2.

UNITED STATES PATENT OFFICE.

SIDNEY O. MARTIN, OF ST. LOUIS, MISSOURI.

AUTOMOBILE SIGNAL DEVICE.

Application filed February 3, 1922. Serial No. 533,939.

To all whom it may concern:

Be it known that I, SIDNEY O. MARTIN, a citizen of the United States of America, residing at St. Louis, in the county of St. Louis and State of Missouri, have invented certain new and useful Improvements in Automobile Signal Devices; and I do hereby declare that the following is a full, clear, concise, and exact description of the invention, such as will enable others skilled in the art to which it appertains to make and use the same.

This invention relates to improvements in illuminated signals, having for an object to provide an illuminated signal or direction indicator for indicating to traffic both on-coming and following the course to be traversed by a vehicle so equipped and likewise, to convey to the drivers or operators of vehicles in such traffic the intention of the driver of the equipped vehicle as to the speed of the same or if it is to be fully stopped.

Another object of the invention is the provision of a device of this character with means actuated by the brake and clutch for automatically illuminating the signal or direction indicator.

Among other aims and objects of the invention may be recited the provision of a signal of the character mentioned with a view towards compactness and in which the number of parts is few, the construction simple, the cost of production small and efficiency in operation high.

Other objects will be in part obvious and in part pointed out hereinafter.

In order that the invention and its mode of operation may be readily understood by persons skilled in the art, I have in the accompanying illustrative drawings and in the detailed following description based thereon, set out one possible embodiment of the same.

In these drawings:

Figure 1 is a general view of the improved signal means partly in elevation and partly in section and disclosing the circuits.

Figure 2 is a detail thereof showing one of the pedal arrangements.

Having more particular reference to the drawings, in connection with which like characters of reference will designate corresponding parts throughout, the improved signal may be stated to consist of a substantially rectangular housing 1, preferably formed of sheet metal and coated with some suitable composition, such as enamel, paint, *et cetera*.

In order that the course about to be traversed by a vehicle equipped with the improved illuminated signal may be conveyed to on-coming traffic and thus permit it to alter the course of the particular vehicles accordingly, panels 12 and 13 are arranged in the open front sides and have the words "Right" and "Left" presented thereupon. Thus, it will be understood that with illumination of the particular compartments, the light rays emitted therefrom will be permitted to reflect through the translucent panels and by consequence, illuminate the same so that they may be readily seen by persons in vehicles constituting the said on-coming traffic.

Other panels of translucent material 14 and 15, are arranged in the opposite open sides, these particular panels having the words "Stop" and "Slow" presented thereupon so that when their particular compartments are illuminated, said translucent panels will be clearly displayed for view and accordingly, will enable operators or drivers of vehicles in the following traffic to control such vehicles.

It of course will be understood that I intend to have the translucent panels 12, 13, 14, 15, colored differently, in order that they may be readily discerned.

Arranged on the under side of the foot-board 18 or other suitable location, is the metal casing 19, the rearward end 20 of which is rounded as shown, and the sides of which have longitudinally disposed slots 21 arranged adjacent the forward portion of said casing.

An arm 22 is pivotally mounted in the metal casing 19 and to the left of the center thereof, said arm having its inner end

bent upon itself so as to form the substantially semi-circular portion 23, carrying a contact 24. A spring 25 normally holds the arm 22 in its extreme right hand position 5 against the peg 26.

A substantially U-shaped member 27 is pivotally mounted as at 28 within the casing 19, adjacent to and spaced from the rounded portion 20 thereof. A spring 29 10 normally holds the left hand portion 30 of said pivoted member 27 in engagement with the peg 31. A contact 32 is carried by said left hand portion 30 and is adapted to form a connection with the contact 24 when the 15 tension of the spring 25 is overcome.

An arm 33 having a C-shaped portion 34 arranged on one end is pivotally mounted to the casing 19, to the right of the center thereof, as at 35. The C-shaped portion 34 20 carries a contact 36 adapted to engage the contact 37 carried by the right hand portion 38 of the member 27, said portion 38 of the member 27 being bent upon itself so as to be arranged within the curve of the C-shaped end of the arm 33, upon the overcoming of the tension of the spring 39 which holds the arm 33 in its normal or circuit breaking position.

A coil spring 40 connects the protruding end of the arm 22 to the clutch pedal 41 of the automobile. A similar spring 42 connects the protruding end of the arm 33 with the brake pedal 43. Suitable clips 44 are used to secure the coiled springs 40 and 42 35 to the pedals 41 and 43, respectively.

Upon depression of the clutch pedal 41, the arm 22 slides forwardly in the slot 21 and thereby forces the contact 24 into engagement with the contact 32 thereby closing the circuit 45 to the compartment marked "Slow" and illuminating said signal as described. Upon depression of the brake pedal 43, the arm 33 slides in the slot 22 thereby forcing the contact 36 into engagement with the contact 37 thereby closing the circuit 46 which illuminates the panel marked "Stop". The force exerted by the arm 33 upon the pivoted member 27 disengages the contacts 24 and 32 thereby 45 breaking the circuit to the panel marked "Slow". Upon release of the brake, the circuit is broken and the arm 33 returns to its normal position, being acted upon by the spring 39, thereby allowing the member 27 55 to resume its normal or central position.

The compartments marked "Right" and "Left" are illuminated at the driver's will by means of the oval push buttons 47 and 48 respectively arranged on the periphery of 60 the steering wheel 49.

From the foregoing, it will be understood that I have provided an extremely simple, novel and compact form of direction indicator, especially advantageous for use in 65 connection with motor driven vehicles, the

arrangement of the translucent signs therein enabling an operator of a vehicle so equipped to selectively signal to following or on-coming traffic his intentions and therefore, to permit the operators or drivers of 70 vehicles constituting the on-coming or following traffic to control the movement of their particular vehicles accordingly.

Manifestly, the construction shown is capable of considerable modification and such 75 modification as is within the scope of my claims, I consider within the spirit of my invention.

I claim:

1. In a device of the character described, 80 the combination with automobile operating pedals and an electrically actuated signal device including separately operable signals; of a casing, pivoted arms arranged in said casing, springs connecting said arms to the respective operating pedals, contacts on 85 said arms, a U-shaped member pivotally mounted in said casing, other contacts carried by the opposite ends of said U-shaped member and positioned for engagement by the first contacts selectively whereby to selectively operate the signals.

2. A circuit closer for use in automobile signaling circuits and adapted for operation by movement of the operating pedal of the 95 automobile, said circuit closer comprising a casing having longitudinally arranged slots in the sides thereof, arms pivotally mounted in said casing and each having an end projecting through a respective slot, springs 100 connecting the projecting ends with the pedals, an inverted U-shaped member pivotally mounted at its center within the casing at the upper part thereof and having its legs terminating near the inner ends of the respective arms, normally spaced contacts on the adjacent ends of the arms, and U-shaped member, the movement of the arms by the 105 pedals effecting engagement between the respective contacts, and springs urging the 110 arms and U-shaped member into normally disengaged position.

3. A circuit closer for automobile signal circuits comprising a casing, an inverted U-shaped member pivoted at the upper part of 115 the casing and having its legs extending downward, one of said legs terminating in an inwardly curved up-turned portion, electrical contacts on the extremity of said legs, an arm pivoted within the casing and having one end extending outward therefrom, the other end of said arm being curved around the last mentioned leg of the U-shaped member and terminating adjacent the end of said leg, a contact on said arm 120 and engageable with the contact on the up-turned leg upon movement of the arm on its pivot, a second arm pivoted within the casing and having its inner end terminating adjacent the end of the remaining leg of the 130

U-shaped member, the inner second arm being provided with a contact movable into engagement with the member contact upon movement of the second arm, a stop limiting 5 movement of the U-shaped member in one direction, a spring normally holding the U-shaped member against said stop, and other

springs normally holding the arms out of engagement with the U-shaped fitted member. ¹⁰

In witness whereof I have hereunto set my hand.

SIDNEY O. MARTIN.
